DANIEL A. GILLEN, OF NEW YORK, N. Y.

ALARM DEVICE

Application filed February 1, 1930. Serial No. 425,276.

This invention relates to alarm devices.

It is among the objects of the present invention to provide in combination with an alarm device, means for discharging material in conjunction with the actuation of the alarm device.

A further object of the present invention is to provide an alarm device including a casing, adapted to receive a cartridge and a spring-10 urged firing pin for the cartridge, together with a container arranged for fracture by the discharge of the cartridge whereby the sound of the explosion will provide an alarm and the fracturing of the container will provide 15 for the dissemination of gas or liquid whereby the device may be used as a fire extinguisher or to provide burglar protection.

A further object of the present invention is to provide in combination with a cartridge 20 and container adapted to be fractured therewith, a separate alarm means associated by cables or the like, whereby it will be operated at a distant point simultaneously with the explosion of the cartridge.

25 Another important object of the present invention is to provide in a device of the character described, thermal means whereby the same will be automatically operated by heat.

Other important objects of the present invention include the novel combination and 30 interrelation of parts, whereby the whole forms a novel, simple and improved device well adapted to meet the demands of economic manufacture.

35 Other objects of the present invention will be apparent from a consideration of the following specification taken in conjunction with the accompanying drawings, in which

Figure 1 is a perspective view of one form 40 of the present invention;

Fig. 2 is a sectional view taken on the line 2-2 of Fig. 1;

Fig. 3 is a top plan view of the device.

Referring more particularly to the drawings, it will be seen that the preferred embodiment of the invention as here illustrated, includes a body 10, which constitutes a chamber within which a firing pin 11 is longitudinally movable. Within the chamber there is 45 provided a coil spring 12, which surrounds

the firing pin, its upper end bearing against the upper end of the chamber, while its lower end bears against a washer 13 connected to the firing pin by a suitable nut 14 adjacent its lower end. The lower end of the chamber is 55 reduced as at 15 to provide a cartridge receiving and holding portion. As indicated in Fig. 2, the cartridge 16 is adapted to be retained in the chamber and extend from the lower reduced portion 15 thereof, the cartridge being retained by the coaction of the cartridge flange with the shoulder of the chamber at the reduced portion thereof.

Associated with the chamber, a receptacle, here shown in the form of a bottle 17, is provided. The neck of the bottle receives therein the lower end of the cartridge 16, which forms a seal therefor. The receptacle 17 is supported on the bottom of a protecting wire screen 18, which is secured from the body 10 60 by a connecting screw 19.

From the foregoing, it will be seen that when the firing pin 11 is released in a manner hereinafter to be described, the spring 12 urges the pin downwardly whereby it contacts with the cartridge 16 to detonate the same. The explosion of the cartridge drives the wads therefrom into the receptacle which is fractured by the explosion, thus disseminating 75 the fluid of the receptacle at the time of 80 the explosion.

By this construction it will be seen that the device is adapted for use as a combined fire extinguisher and fire alarm. The fluid in the bottle in such case will be suitable fire 85 extinguishing fluid and the explosion of the cartridge will provide an alarm at the same time the fluid puts out the fire.

As shown in Figs. 1 and 2, it may be preferable to suspend the device by a link construction, whereby the recoil of the cartridge will act to swing the device so that the fluid will be completely delivered and scattered over a wide area. As shown in Fig. 2, the fluid in the receptacle is preferably provided 95 with an easily fracturable plug, such as paraffin, indicated at 20, thus evaporation of the fluid is prevented and sealing of the receptacle by the cartridge need not be relied upon to prevent such evaporation.

This construction also provides for the use of the device as a burglar alarm. The release of the firing pin will cause an explosion which will frighten the burglar, and, at the same time, give a general alarm. In such case, the fluid within the receptacle may be some form of obnoxious gas, such as tear gas, the discharge of which will affect the burglar and prevent his escape.

For controlling the firing pin, the upper end thereof is bent in the form of a hook. As indicated at 21 the hook engages a securing member 22, which is preferably of stranded wire, its upper end being associated in suitable manner with material having a low heating point. The body 10 above the chamber extends into a narrow supporting neck which is provided with a bifurcated portion 23, the furcations of which receive therebetween the securing member 22. The head 24 of the securing member, which is formed by the embedding of the strands thereof with the thermal responsive metal, is supported upon the upper surfaces of the furcations, the arrangement being such that upon the application of heat, the material of the head 24 will melt, thus releasing the securing member and also releasing the firing pin. In this connection it is important to note that the securing member 22 is of stranded wire, otherwise a securement thereof with the thermal responsive metal is impracticable.

For preventing accidental discharge of the device, a retaining wire 25 is provided, which is secured through an aperture in the extension of the body and extends to the securing member 22, whereby the member will be prevented from downward movement to release the firing pin. This construction provides for the escapement of the device loaded without danger of accidental discharge. When the device is to be used, the retaining member 25 is, of course, removed. With this construction it will be seen that the device automatically operates as a fire alarm and fire extinguisher when the temperature has reached a predetermined point.

For manually releasing the firing pin, a cord 26, as shown in Fig. 1, is provided, which may extend over one or more suitable pulleys, as indicated at 27, to have the operating end 28 in any desired position. The cord 26 surrounds the retaining member 22 adjacent the bifurcated portion 23, whereby the cord may exert a pull upon the retaining member to move it from between the furcations, thus releasing the firing pin. This feature of the present invention may be used when the device is to be used as a fire extinguisher, or, as is more preferable, it is designed for use when an obnoxious gas is contained within the receptacle and it is used as a burglar alarm. Thus in banks or the like, the device may be mounted near the ceiling in front of the cashier's cage and the operating cord 26 may

extend into the cage so that a pull thereon by the cashier will cause an explosion alarm and, at the same time, discharge gas upon any one attempting to burglarize.

In many instances it may be preferable to provide a separate alarm means operable with the discharge of the cartridge at a remote place. This may be suitably accomplished by the attachment with the end 21 of the firing pin 11, of a hook 30, which is connected with a cord or cable 31 and extends to a mechanical alarm bell 32. Upon downward movement of the firing pin, either in response to heat change or by manual operation of the cord 26, the hook 30 will move down carrying with it the cable 31, which releases a conventional releasing dog 33 of the bell structure. The bell is preferably arranged to continue its alarm over a specific length of time, such as ten minutes, whereby the device provides for the remote control of an associated alarm apparatus.

From the foregoing it will readily be seen that the invention provides an alarm mechanism adapted to discharge material which may be used as a fire extinguisher or as a burglar alarm, or as a burglary prevention device. It will be understood that the arrangement of cables 26 and 31 may be in any suitable manner such as to facilitate the manual operation of the device or the control of the remotely positioned alarm mechanism. It will thus be understood that the invention is not specifically confined to the specific structural details herein presented, but that numerous changes, modifications and the full use of equivalents may be resorted to without departing from the spirit or scope of the invention as outlined in the appended claims.

What is claimed is:

1. In a device of the character described, a cartridge-receiving casing, and means for associating a receptacle with said casing, whereby the explosion of a cartridge in said casing will rupture said receptacle, said casing including a firing pin arranged for movement therein to explode said cartridge.

2. In a device of the character described, a cartridge-receiving casing, and means for associating a receptacle with said casing, whereby the explosion of a cartridge in said casing will rupture said receptacle, said casing including a firing pin arranged for movement therein to explode said cartridge, said casing further including a spring means for urging said pin toward said cartridge.

3. In a device of the character described, a cartridge-receiving casing, means for associating a receptacle with said casing, whereby the explosion of a cartridge in said casing will rupture said receptacle, said casing including a firing pin arranged for movement therein to explode said cartridge, said casing further including a spring means for urging said pin toward said cartridge, and releasable means

- for retaining said pin against the tension of said spring means.
4. In a device of the character described, a cartridge-receiving casing, means for associating a receptacle with said casing, whereby the explosion of a cartridge in said casing will rupture said receptacle, said casing including a firing pin arranged for movement therein to explode said cartridge, said casing further including a spring means for urging said pin toward said cartridge, and releasable means for retaining said pin against the tension of said spring means, said releasable means including a retaining member releasably engaged by an extending portion of said casing. 70
5. In a device of the character described, a cartridge-receiving casing, means for associating a receptacle with said casing, whereby the explosion of a cartridge in said casing will rupture said receptacle, said casing including a firing pin arranged for movement therein to explode said cartridge, said casing further including spring means for urging said pin toward said cartridge, and releasable means for retaining said pin against the tension of said spring means, said releasable means including a retaining member releasably engaged by an extending portion of said casing, said casing including an upwardly-extending portion having a bifurcated extremity adapted to receive between the furcations thereof, said retaining member, and manual means for releasing said retaining member from said furcations. 75
6. In a device of the character described, a cartridge-receiving casing, means for associating a receptacle with said casing, whereby the explosion of a cartridge in said casing will rupture said receptacle, said casing including a firing pin arranged for movement therein to explode said cartridge, said casing further including spring means for urging said pin toward said cartridge, and releasable means for retaining said pin against the tension of said spring means, said releasable means including a retaining member releasably engaged by an extending portion of said casing, said casing including an upwardly-extending portion having a bifurcated extremity adapted to receive between the furcations thereof, said retaining member. 80
7. In a device of the character described, a cartridge-receiving casing, means for associating a receptacle with said casing, whereby the explosion of a cartridge in said casing will rupture said receptacle, said casing including a firing pin arranged for movement therein to explode said cartridge, said casing further including spring means for urging said pin toward said cartridge, and releasable means for retaining said pin against the tension of said spring means, said releasable means including a retaining member releasably engaged by an extending portion of said casing, said casing including an upwardly-extending portion having a bifurcated extremity adapted to receive between the furcations thereof, said retaining member, the upper end of said member being retained by said bifurcated portion by fusible construction, and manual means for releasing said retaining member from said furcations. 85
8. In a device of the character described, a cartridge-receiving casing, means for associating a receptacle with said casing, whereby the explosion of a cartridge in said casing will rupture said receptacle, said casing including a firing pin arranged for movement therein to explode said cartridge, said casing further including spring means for urging said pin toward said cartridge, releasable means for retaining said pin against the tension of said spring means, said releasable means including a retaining member releasably engaged by an extending portion of said casing, said casing including an upwardly-extending portion having a bifurcated extremity adapted to receive between the furcations thereof, said retaining member, the upper end of said member being retained by said bifurcated portion by fusible construction, and manual means for releasing said retaining member from said furcations. 90
9. In a device of the character described, a cartridge-receiving casing, means for associating a receptacle with said casing, whereby the explosion of a cartridge in said casing will rupture said receptacle, said casing including a firing pin arranged for movement therein to explode said cartridge, said casing further including spring means for urging said pin toward said cartridge, releasable means for retaining said pin against the tension of said spring means, said releasable means including a retaining member releasably engaged by an extending portion of said casing, said casing including an upwardly-extending portion having a bifurcated extremity adapted to receive between the furcations thereof, said retaining member, the upper end of said member being retained by said bifurcated portion by fusible construction, and manual means for releasing said retaining member from said furcations. 95
10. In a device of the character described, a cartridge-receiving casing, and means for associating a receptacle with said casing, whereby the explosion of a cartridge in said casing will rupture said receptacle, said casing including means therein for exploding said cartridge. 100
11. In a device of the character described, a cartridge-receiving casing, and means for associating a receptacle with said casing, whereby the explosion of a cartridge in said casing will rupture said receptacle, said casing including movable means therein for exploding said cartridge. 105
12. In a device of the character described, 110
13. In a device of the character described, 115
14. In a device of the character described, 120
15. In a device of the character described, 125
16. In a device of the character described, 130

a cartridge-receiving casing, and means for associating a receptacle with said casing, whereby the explosion of a cartridge in said casing will rupture said receptacle, said casing including longitudinally movable means therein for exploding said cartridge.

Signed at New York, in the county of New York and State of New York, this 31st day of January, A. D. 1930.
